ROTARY JAR

Sisti Siracusa, Huntington Beach, Calif., assignor
to Pacific Shore Investment Corporation,
Huntington Beach, Calif., a corporation of
California

Application January 28, 1935, Serial No. 3,728

5 Claims. (Cl. 255—27)

My invention relates to rotary jars, and has particular reference to an improvement of the type of rotary jar disclosed in the copending application of George Walter Bowen, Serial No. 5 744,167 filed September 15, 1934, for Adjustable rotary jar, which has matured into Patent No. 2,013,127, issued Sept. 3, 1935.

In the drilling and operation of oil wells, it frequently occurs that various tools employed in the well-hole become stuck therein, and, in order to dislodge the same, it is necessary to produce an impact upon the tool or upon the drill string on which the tool is suspended. For this purpose tools have been devised, known in the art as "jars", those adapted particularly for use in the rotary method of drilling being referred to as "rotary jars".

In the copending application of George Walter Bowen, hereinabove referred to, a particular form 20 of rotary jar is disclosed, in which the jar comprises essentially a bowl or outer member within which is telescopically assembled a mandrel normally connected to the bowl in a contracted position by means of a friction coupling member which, upon the production of a predetermined 25 longitudinal strain between the bowl and mandrel will release the mandrel, permitting rapid movement between the bowl and mandrel until striking abutments on the bowl and mandrel attract each other, thus producing a blow of considerable magnitude directed upwardly upon the 30 drill string. Since the usual practice is to connect a jar in a drill string during the drilling operations, and to drill with the jar in the drill string, it is necessary that the bowl and mandrel 35 shall be employed together against relative rotary movement until it is desired to produce the jarring impact. Again it is necessary to change the adjustment of the friction coupling device in order to adjust the tonnage of the blow produced by the 40 jar and in this application these features are provided for by the employment of splines on the bowl and mandrel interengaging each other to prevent relative rotary movement between the bowl and mandrel until the mandrel and bowl 45 are moved longitudinally relative to each other to position the splines on the mandrel in line with a space between the splines on the bowl, at which time the mandrel and bowl may be rotated relative to each other, and by connecting an adjusting member to the mandrel such relative rotary movement between the bowl and mandrel may be applied to adjust the friction coupling employed for normally holding the bowl and mandrel in contracted position.

It is an object of my invention, however, to provide a jar of the character set forth with adjusting mechanism which will permit the operator 50 of the rotary drilling table to determine accu-

rately how much relative rotation between the bowl and mandrel will be produced at the jar.

Another object of the invention is to provide a rotary jar of the character set forth in which the bowl and mandrel are connected together by means of interengaging splines in which, when the jar is in extended position a predetermined twist may be given the drill string which twist will, upon the resetting of the jar to contracted position, cause relative rotary movement between the bowl and mandrel equal to the twist produced in the drill string.

Another object of the invention is to provide a rotary jar of the character set forth, in which the mandrel and bowl are splined together, and in which the striking abutments on both the bowl and the mandrel are formed with uninterrupted annular surfaces, thus increasing the area of contact and increasing the life of the striking abutments.

Another object of the invention is to provide a rotary jar of the character set forth, in which the mandrel and bowl are connected together by means of splines, the splines on one of said members being interrupted to permit relative rotary movement between the bowl and mandrel, in which certain of the splines extend beyond the limits of the remaining splines to act as guides, directing the splines into alignment with each other.

Another object of the invention is to provide a rotary jar of the character set forth, in which the bowl and mandrel are telescopically assembled and the diameter of that portion of the mandrel which extends from the bowl is substantially equal to the exterior diameter of the bowl, and in which the change from smaller to larger diameter of the mandrel is effected by a gradual enlargement of the diameter.

Another object of the invention is to provide a jar of the character set forth, in which passages are provided between the mandrel and the bowl, permitting liquids to pass therebetween, preventing cushioning of the impact on the jar.

Other objects and advantages will be apparent from a study of the following specifications, read in connection with the accompanying drawings, wherein:

Figure 1 is a vertical sectional view, taken through a jar constructed in accordance with my invention, illustrating the same in contracted position;

Fig. 2 is a sectional view, similar to Fig. 1, illustrating the mandrel and jar in their extended or jarring position;

Fig. 3 is a view similar to Figs. 1 and 2, illustrating the mandrel and bowl in their intermediate position ready for relative rotary movement for adjustment thereof;

Fig. 4 is a development of the splines employed

on the bowl and mandrel of the jar illustrated in Fig. 1;

Figs. 5 and 6 are detailed horizontal sectional views of the bowl and mandrel, respectively, 5 taken along lines V—VI—V—VI, of Fig. 1;

Fig. 7 is a detailed horizontal sectional view of the mandrel taken along line VII—VII; and

Fig. 8 is a detailed sectional view of the mandrel and bowl taken along line VIII—VIII of 10 Fig. 1.

Referring to the drawings, I have illustrated herein a jar comprising an outer, or bowl, member 1, the upper end of which is threaded as at 2, to receive the pin 3 of the end of a drill string 15 employed for transmitting rotary drilling forces from a rotary drilling apparatus at the top of the well. Telescopically assembled within the bowl 1 is a mandrel 4 having an enlarged portion 5 thereof constituting a striking abutment 20 or jarring hammer adapted to strike upon a striking abutment 6 formed upon the interior of the bowl 1. The striking abutment 6 is preferably formed upon a nut 7 screwed into the lower end of the bowl 1, as indicated at 8, the upper end 25 of the nut 7 having an annular face forming the abutment 6 upon which the annular lower surface 9 of the enlargement 5 on the mandrel may strike.

The upper end of the mandrel 4 is illustrated 30 as being formed as a friction head 10 having a plurality of radially extending flanges 11 formed thereon, these flanges being spaced from each other longitudinally along the friction head 10 to constitute interengaging members engaging inwardly extending radial flanges 12 formed upon a friction sleeve or slip 13 so that when the mandrel and bowl are in the contracted position shown in Fig. 1 the flanges 11 of the friction head will engage above the flanges 12 on the friction 35 sleeve and the mandrel and bowl will thus be held in contracted position against relative longitudinal movement until such longitudinal strain is produced between the bowl and mandrel as will cause the flanges 11 and 12 to slip by each 40 other, at which time the bowl and mandrel will be free to move rapidly to the extended position 45 shown in Fig. 3, bringing the abutment surfaces 9 and 6 of the two members into jarring relation.

As will be understood by those skilled in the 50 art, the friction sleeve 13 is preferably provided with a plurality of outward radially extending flanges 14 spaced longitudinally of the sleeve 13 at points lying between the radial flanges 12 thereof, so that each portion of the sleeve 13 55 constitutes a bridge-like member permitting the sleeve 13 to spring outwardly when a predetermined longitudinal strain is exerted between the bowl and mandrel. The friction sleeve 13 is preferably tapered upon its outer surface to conform 60 with the tapered bore 15 of the interior of the bowl 1 so that by moving the friction sleeve 13 upwardly and downwardly relative to the bowl, the amount of longitudinal strain necessary to pass the flanges 11 and 12 past each other may be 65 suitably decreased or increased, respectively.

In order to provide for such adjustable movement of the sleeve 13 relative to the bowl, or, more accurately, in order to adjustably limit the 70 distance down the tapered bore 15 to which the sleeve 13 may travel, I provide a supporting ring 16 threaded as at 17 into the interior of the bowl 1 so that by rotating the ring 16 relative to the bowl 1, the ring may be moved upwardly and downwardly in the bowl to thereby adjust the 75 amount of strain which must be placed in the

drill string in order to disengage the friction head 10 from the friction sleeve 13.

In order to permit the bowl and mandrel, when extended, to be reset without requiring the same amount of stress between the members as was required to jar them, the space between the mandrel and bowl immediately above the spring 13 may be sufficiently large to allow the spring sleeve 13 to move upwardly therein away from the tapered bore 15 thus permitting the friction head 10 and the sleeve 13 to pass each other with the minimum amount of resistance, while a coil spring 18 may be provided bearing upon the upper end of the sleeve 13 to normally seat the friction sleeve 13 tightly in the tapered bore 15 15 after the bowl and mandrel have been returned to their contracted position, as shown in Fig. 1.

As stated hereinbefore it is necessary, during the normal operation of a drill string to rotate 20 tools which may be suspended from the drill string, and for this reason it is necessary to provide some means interengaging the bowl and mandrel to permit rotary forces therebetween to drilling tool which may be connected to the 25 extending end 19 of the mandrel 4. For this purpose I have provided the interior of the bowl 1 with inwardly extending splines 20 adapted to engage corresponding outwardly extending splines 21 formed upon the mandrel 4 when the 30 bowl and mandrel are in their contracted position, as shown in Fig. 1.

It will also be observed that the upper end of the mandrel 4 is likewise provided with splines 22 aligned with splines 21 and adapted to engage 35 the bowl splines 20 when the bowl and mandrel are in their extended, or jarring, position, as shown in Fig. 2. Thus when the bowl and mandrel are in either their fully extended position or fully contracted position rotary forces may be 40 transmitted directly between the bowl and the mandrel. However, when the bowl and the mandrel are in their intermediate position, as shown in Fig. 3, the bowl splines 20 will lie in the space between the splines 20 and 22 of the 45 mandrel 4 and at this position rotation of the drill string will rotate the bowl 1 without correspondingly rotating the mandrel 4. Thus when the mandrel and bowl are in their intermediate 50 position rotary movement imparted by rotation of the drill string will cause the bowl to be rotated relative to the adjusting ring 16, the ring 16 being provided with inwardly extending splines 23 engaging suitable keyways 24 on the friction head of the mandrel 4, and in this manner the ring 16 may be adjusted upwardly and downwardly in the bowl 1 to vary the strain required to disengage the friction head 10 and the sleeve 13 and thus vary the tonnage of blow 55 produced when the jar is actuated.

It will be noted that all of the bowl splines 20 are provided with beveled upper and lower surfaces, as indicated at 20a, to present knife edges to the mandrel splines 21, 22, thus assisting in guiding the bowl splines into the space 65 between the mandrel splines as the bowl and mandrel are moved either to contracted position or extended position.

It will also be noted that one or more of the mandrel splines extend beyond the limits of the 70 remaining mandrel splines, the extending splines indicated by the reference characters 21a and 22a constituting guide splines, each having their outer surfaces beveled to engage the beveled surfaces of the bowl splines and guide the mandrel 75

splines and bowl splines into accurate engagement when the bowl and mandrel are moved to their different positions. The extending mandrel and bowl splines will, as indicated in Fig. 3, 5 provide only a very short distance of travel between the bowl and mandrel free of engagement of the splines and thus when no rotary torsion is placed in the drill string the mandrel and bowl will be forced to move in direct longitudinal 10 alignment with each other.

However, when it is desired to adjust the rings 16, exact and accurate adjustment thereof may be effectively performed by placing a predetermined amount of torsion in the drill string, while 15 the bowl and mandrel are in their extended position, as shown in Fig. 2, and thus, as soon as the drill string is lowered to reset the jar into contracted position, the torsion will rotate the bowl relative to the mandrel when the guide 20 spline 22a just clears the mandrel spline, but, as will be observed from an inspection of Fig. 3, the total distance between the extending ends of the guide splines 21a and 22a is so minute 25 that the rotary movement permitted the bowl will be only such as will cause the guide spline 21a to engage in the next space between the mandrel and splines, thus insuring that the amount of adjustment of the ring 16 will be only 30 the space of one spline upon each operation. In the form of the device illustrated therein, there are six splines on the bowl, and six splines on the mandrel. Thus the operator of the rotary table may place one-sixth of a revolution torsion in the drill string when the bowl and mandrel 35 are in extended position, and upon lowering the drill string the splines will be moved relative to each other one space, adjusting the ring 16 one-sixth of a revolution.

As will be understood by those skilled in the art, the normal operation of the jar would be to 40 merely place a longitudinal strain without torsion in the drill string operating the jar to produce the impact which may be repeated as often as is desired in an effort to dislodge the tool. But if such repeated jarring fails to dislodge the tool, the operator may produce accurate impact 45 by successively adjusting the ring 16 by successively placing one-sixth revolution torsion in the drill string, as described above, and increase the tonnage blow to the point necessary to dislodge 50 the tool.

By the employment of the guide splines and the pointed or beveled ends on the bowl splines, the operator of the rotary table will be enabled 55 to adjust the ring 16 with complete accuracy, since he will know that upon each adjustment operation one-sixth of a revolution adjustment will be produced, and after the tool has been dislodged the operator may then turn the bowl and mandrel relative to each other back to their original or minimum adjustment position and continue the drilling operations with the jar again set to produce the minimum tonnage of blow.

As will be understood by those skilled in the art, the space between the bowl and mandrel is 60 frequently filled with drilling fluid, mud, and the like, so that the movement of the enlarged head 5 toward the nut 6 upon each jarring operation will force such fluid out of the space between the bowl and the mandrel. The pressure which will 65 be built up in the fluid during its expulsion from the space between the bowl and the mandrel will act as a cushion, absorbing a great portion of the force desired to be produced as an impact in 70

the jar. To overcome this absorption of the jarring force, I provide upon the mandrel head 5 a plurality of relatively shallow grooves 25 preferably extending longitudinally of the mandrel head 5 and spaced between the splines 21. 5 These grooves 25 provide liquid passages which will permit liquid to be readily passed from the space between the bowl and mandrel past the head 5. Similarly the nut 7 may be provided with longitudinal shallow grooves 26 communicating with the exterior of the bowl 1 so that liquid may readily be forced from the space between the bowl and mandrel outwardly of the bowl. By employing the two sets of drilled shallow grooves substantially no resistance will be 15 built up in any liquid which may lie in the space between the bowl and mandrel and the full force exerted on the drill string will be transmitted directly between the striking faces 9 and 6.

Again by referring particularly to Fig. 1, it will 20 be observed that the extending end 19 of the mandrel is in the bowl extending below a diameter substantially equal to the exterior diameter of the bowl, while the body portion of the mandrel 4, which lies within the bowl, is of considerably 25 reduced diameter to permit the formation of a relatively wide striking abutment 6 on the nut 7. If the reduced diameter and enlarged diameter of the mandrel are sharply defined, the junction of the reduced and large diameters of the mandrel 30 will form the weakest point along the length of the mandrel and in actual experience it has been found that this fatigue in the mandrel occurs most rapidly at this point. The strength and 35 life of the mandrel may be considerably increased by gradually changing the diameter of the mandrel as by tapering the mandrel outwardly, as indicated at 27, partially tapering the interior of the nut 7 to conform with the taper 27 of the mandrel. Thus the weakness of the mandrel is 40 distributed over a considerable portion of the length of the mandrel, providing substantially no point or line along which the fatigue may concentrate.

While I have shown and described the preferred embodiment of my invention, it is to be understood that I do not wish to be limited to any of the details of construction shown herein, except as defined in the appended claims.

I claim:

1. In a jar for use in rotary drilling, a bowl member and a mandrel member telescopically assembled for longitudinal movement relative to each other from a contracted position to an extended position, striking abutments on said bowl 55 and mandrel members interengageable when said members are in extended position, friction means on said bowl and mandrel members holding said members in contracted position but releasable by the exertion of a predetermined longitudinal 60 strain between said members, means actuated by relative rotation of said bowl and mandrel members for adjusting said friction means to vary the strain required to release it, means interconnecting said bowl and mandrel members 65 against relative rotation when said members are in either said contracted position or said extended position but permitting said relative rotation when said members are in an intermediate position, and guide means on said interconnecting 70 means for guiding said interconnecting means into connecting relation when said members are moved toward either said contracted position or said extended position.

2. In a jar for use in rotary drilling, a bowl 75

- member and a mandrel member telescopically assembled for longitudinal movement relative to each other from a contracted position to an extended position, striking abutments on said bowl and mandrel members interengageable when said members are in extended position, friction means on said bowl and mandrel members holding said members in contracted position but releasable by the exertion of a predetermined longitudinal strain between said members, means actuated by relative rotation of said bowl and mandrel members for adjusting said friction means to vary the strain required to release it, means interconnecting said bowl and mandrel members against relative rotation when said members are in either said contracted position or said extended position but permitting said relative rotation when said members are in an intermediate position, said interconnecting means including a plurality of longitudinally extending splines formed upon one of said members equally spaced circumferentially about said member, one or more cooperating splines formed upon the other of said members engageable in the spaces between said first-named splines, one of said last-named splines having a length greater than the remainder thereof to engage in one of said spaces to guide said splines into engagement when said bowl and mandrel members are moved between said contracted position and said extended position.
3. In a jar for use in rotary drilling, a bowl member and a mandrel member telescopically assembled for longitudinal movement relative to each other from a contracted position to an extended position, striking abutments on said bowl and mandrel members interengageable when said members are in extended position, friction means on said bowl and mandrel members holding said members in contracted position but releasable by the exertion of a predetermined longitudinal strain between said members, means actuated by relative rotation of said bowl and mandrel members for adjusting said friction means to vary the strain required to release it, means interconnecting said bowl and mandrel members against relative rotation when said members are in either said contracted position or said extended position but permitting said relative rotation when said members are in an intermediate position, a plurality of longitudinally extending splines formed on said bowl and having a length less than the distance of telescopic movement of said bowl and mandrel members, cooperating splines on said mandrel comprising two groups of splines spaced longitudinally of said mandrel, one of said groups engaging said bowl splines when said mandrel and bowl are in extended position, the other of said groups engaging said bowl splines when said mandrel and bowl are in contracted position, the spacing of said groups being equal to the length of said bowl splines, one or more of said mandrel splines extending into said space between said groups to constitute a guide spline guiding said mandrel and bowl splines into interengaging position.
4. In a jar for use in rotary drilling, a bowl member and a mandrel member telescopically assembled for longitudinal movement relative to each other from a contracted position to an extended position, striking abutments on said bowl and mandrel members interengageable when said members are in extended position, friction means

on said bowl and mandrel members holding said members in contracted position but releasable by the exertion of a predetermined longitudinal strain between said members, means actuated by relative rotation of said bowl and mandrel members for adjusting said friction means to vary the strain required to release it, means interconnecting said bowl and mandrel members against relative rotation when said members are in either said contracted position or said extended position but permitting said relative rotation when said members are in an intermediate position, a plurality of longitudinally extending splines formed on said bowl and having a length less than the distance of telescopic movement of said bowl and mandrel members, cooperating splines on said mandrel comprising two groups of splines spaced longitudinally of said mandrel, one of said groups engaging said bowl splines when said mandrel and bowl are in extended position, the other of said groups engaging said bowl splines when said mandrel and bowl are in contracted position, the spacing of said groups being equal to the length of said bowl splines, and the ends of said bowl splines being of reduced area to form guide surfaces guiding said mandrel and bowl splines into interengaging position.

5. In a jar for use in rotary drilling, a bowl member and a mandrel member telescopically assembled for longitudinal movement relative to each other from a contracted position to an extended position, striking abutments on said bowl and mandrel members interengageable when said members are in extended position, friction means on said bowl and mandrel members holding said members in contracted position but releasable by the exertion of a predetermined longitudinal strain between said members, means actuated by relative rotation of said bowl and mandrel members for adjusting said friction means to vary the strain required to release it, means interconnecting said bowl and mandrel members against relative rotation when said members are in either said contracted position or said extended position but permitting said relative rotation when said members are in an intermediate position, a plurality of longitudinally extending splines formed on said bowl and having a length less than the distance of telescopic movement of said bowl and mandrel members, cooperating splines on said mandrel comprising two groups of splines spaced longitudinally of said mandrel, one of said groups engaging said bowl splines when said mandrel and bowl are in extended position, the other of said groups engaging said bowl splines when said mandrel and bowl are in contracted position, the spacing of said groups being equal to the length of said bowl splines, and the ends of said bowl splines being of reduced area to form guide surfaces guiding said mandrel and bowl splines into interengaging position, one of said mandrel splines extending into said space between said groups to constitute a guide engaging said bowl splines immediately after separation of said bowl and mandrel splines whereby a torsional strain placed upon said mandrel and bowl members will, upon longitudinal relative movement of said members, cause relative rotation of said members equal to the spacing between adjacent bowl splines.
